BOWLING TROPHY

Chester Urban, 2832 Wilmot St.,
Philadelphia, Pa. 19137

Filed Feb. 15, 1973, Ser. No. 332,842

Term of patent 14 years

Int. Cl. D11—02

U.S. Cl. D29—28 A

FIG. 1

FIG. 2

FIG. 4

FIG. 5

FIG. 3

FIG. 6

FIG. 7

FIG. 8

FIG. 9

FIG. 10

FIG. 11

FIG. 12

FIG. 1 is a front elevational view of a bowling trophy showing my new design;

FIG. 2 is a left side elevational view thereof;

FIG. 3 is a right side elevational view thereof;

FIG. 4 is a top plan view thereof;

FIG. 5 is a bottom view thereof;

FIG. 6 is a rear elevational view thereof on a 1 to 2 scale with respect to FIG. 1;

FIG. 7 is a front elevational view of a bowling trophy showing a modified form of my new design;

FIG. 8 is a left side elevational view thereof;

FIG. 9 is a right side elevational view thereof;

FIG. 10 is a top plan view thereof;

FIG. 11 is a bottom elevational view thereof;

FIG. 12 is a rear elevational view thereof on a 1 to 2 scale with respect to FIG. 7.

I claim:

The ornamental design for bowling trophy, substantially as shown and described.
